GOLF FLAG

Vincent Vigliotti, Great Neck, N. Y.

Application March 23, 1935, Serial No. 12,547

3 Claims. (Cl. 116—173)

The present invention relates to golf flags. An object of the present invention is to provide a golf flag which is revolvable about the vertical axis of the staff on which it is mounted so as to 5 offer a ready indication of the direction in which the wind is blowing. In the preferred constructions, the flag is supported on ball bearings so as to swing with the utmost freedom.

A further object of the present invention is to 10 provide an improved flag having a rigid metal frame for supporting the panel forming the flag body.

The accompanying drawing shows, for purposes of illustrating the present invention, two 15 of the many embodiments in which the invention may take form, it being understood that the drawing is illustrative of the invention rather than limiting the same. In this drawing:

Fig. 1 is a side elevational view of a complete 20 flag for golf holes;

Fig. 2 is a view illustrating the flag partly assembled;

Fig. 3 is a vertical sectional view through the 25 flag; and

Fig. 4 is a top plan view of a modified form of construction.

The complete flag has a staff 10 of suitable length adapted to be placed in the usual manner. This staff carries a threaded insert 11 at its 30 upper end.

The top unit of the complete flag is secured on to the upper end of the staff. This top unit includes a relatively fixed shaft 12 having a reduced threaded end 13 to fit the tapped insert 35 11. This shaft is reduced at its upper end as indicated at 14, and ball bearings 15 and 16 are carried on the reduced ends of the shaft. These ball bearings are received in a tube 17, whose ends are bored out to provide shoulders as indicated 40 at 18 and 19.

The upper end of the shaft 12 is threaded at 20 and a cap 21 secured in place. The cap extends down past the upper end of the tube 17 to keep the rain from entering the tube, but does 45 not tightly fit it.

The tube 17 is apertured to receive two laterally extending rods 22 and 23. These rods have threaded ends and are locked in place by nuts 24 and 25. The flag body is indicated at 50 26. It may be made out of linoleum, oilcloth, fabric, sheet rubber, and the like, and is here shown as being provided with top and bottom hem 27 or the like to receive the rods 22 and 23 and with a vertical hem 28 to receive a rod 29 55 having apertured ends to receive the ends of the

rods 22 and 23. Nuts 30 hold the flag body in place. The metal members or rods keep the body of the flag in shape and protect it against injury or fluttering.

It will be seen that the flag may rotate on the 5 ball bearings so as to swing to the breeze. When the caddy rests the flag on the ground it lies flat and there is nothing to distract the attention of the golfer.

The construction is one which is so designed 10 as to permit cleaning of the flag, replacement of parts, oiling of the bearings, and generally to afford the maximum amount of satisfactory use on the putting green, or elsewhere.

The signal 31 of Fig. 4 has four radiating 15 vanes and will rotate easily.

It is obvious that the invention may be embodied in many forms and constructions and I wish it to be understood that the particular forms shown are but two of the many forms. Various 20 modifications and changes being possible, I do not otherwise limit myself with respect thereto.

What is claimed is:

1. A signal for golf hole flags, comprising a vertical member, two spaced horizontal arms in 25 the same plane, a flag body having hemmed upper and lower edges to receive the arms, and a vertical hem at the outer edge, and a cross member carried in the hem and secured to the outer ends of the arms to keep them in position and 30 prevent fluttering of the flag body.

2. A detachable signal for golf hole flags, and the like, comprising a tube carrying ball bearings adjacent its ends, a shaft carried in the ball bearings, and having a projecting lower end for 35 securing to a fixed support, two spaced horizontal arms in the same plane, a flag body having hemmed upper and lower edges to receive the arms, and a cross member secured to the outer ends of the arms to keep them in position. 40

3. A detachable signal for golf hole flags, and the like, comprising a tube having internal shoulders near its ends, ball bearings adjacent the shoulders, a shaft having reduced ends to fit in the ball bearings, the lower end being threaded below the ball bearing for securing to a tapped support, two spaced horizontal arms in the same plane, a flag body having hemmed upper and lower edges to receive the arms and a vertical hem at the outer edge, and a cross member 50 carried in the hem and secured to the outer ends of the arms to keep them in position and prevent fluttering of the flag body.
